COMBINED NOISEMAKER TOY AND PLACE
CARD HOLDER

David Cohn, Brooklyn, N. Y.

Application December 8, 1939, Serial No. 308,130

12 Claims. (Cl. 46—175)

This invention relates to sound vibrating toys commonly called crickets of various shapes and simple construction, the main object being provision of integral means in such device for holding cards and supporting the cards in substantial upright position the sound reed having double utility, in one instance acting as a base for the card support, and in the other as a sound reed for the toy.

Another object is the provision of an ornamental card holder of 2 simple main parts the body member being shaped to simulate a fruit, insect, bird, or animal to lend decoration to a dining table as a place card holder.

These and other objects will be apparent from the following description and attached drawing forming part hereof.

Fig. 1 is a perspective view of my device shown resting on its base holding a card at its upper end.

Fig. 2 is a longitudinal section view taken on line 2—2 of Fig. 1.

Fig. 3 is a fragmentary view of my device showing another integral fastening means.

Fig. 4 is a rear view of my device showing means integral of the under flanges and also means integral of the base for fastening the device to a garment to display a card in upright position.

Fig. 5 is a plan view of an embodiment showing card holding means formed on an upper integral extension.

Fig. 6 is a section taken on line 6—6 Fig. 5, showing means integral of the upper body portion for pinning the device to a garment.

Fig. 7 is an embodiment showing the device in the form of a flower or the like having means on an extension for card holding and means for pinning the device to a garment for use as a price tag.

Referring to the drawing, 10 represents a stamping of sheet metal in a suitable shape for example as a beetle having at its upper end a substantial transverse upward bowed slot 11, having vertically spaced apart edges 12, 13, which converge toward the respective ends 14, 15 thereof, the lower edges 13 of said slot defining an upwardly directed gripping tongue 16, adapted to engage a card 17, inserted in said slot and laterally flex the same so as to frictionally bind it against the upper edge 12 of the slot.

The lower end 18 of the stamping which is preferably bent at an angle with the upper portion, has 3 bentunder flange edges 181, 182 and 183 which flanges form means to clampingly

hold flat spring metal strip base member 19 on which the device may be at rest to so support suitable card in the device without overturning. Said strip has the usual central depressed portion 195 adapted on vibration thereof to facilitate noisemaking. Any suitable indicia may be on the card such for example as the name of a person so that the card and device may cooperatively be a displayed place card and holder for use on a dinner table. The body of the device 10 may be shaped to simulate insects, birds, fruit, flowers, gems or articles, etc., and may be ornamenteally painted under the lithographing process prior to shaping. When the card has been removed from the slot the device may then be used as a noisemaker or cricket, the spring base acting as a reed for vibration when actuated by a person's thumb the device being held in the hand as is well known in the art.

Other card holding means may be used such as the tongues 16 of Figs. 2 and 7.

In Fig. 4 are shown integral means 191, 184 for fastening the device to a garment or the like, said means being respectively formed either on the spring base or on extension of flange 181. In this embodiment the device may function as a combined price tag and noisemaker. Card-holding means 16 may be formed on an extension 20. (See Figs. 5 and 7.)

The upper and lower portions may be formed in alignment, i. e., in non-angular relationship to facilitate fastening the device to the garment and having a pin 101 integral of the upper body portion as shown in Figs. 5 and 7.

It is seen there is provided a novel combined cardholder and toy of 2 parts and economical in cost, the base of which has double function, and in one embodiment, i. e., Fig. 4, possible triple function namely as a base or a reed, or as a fastening means.

Parts may be used without others. The disclosure is intended to be illustrative rather than limitative.

I claim,

1. In a toy noisemaker comprising a stamping of sheet metal having upper and lower arched portions, the combination of, means integral and cooperative with the stamping forming a combined port and a card-retaining-slot, the lower portion having bentunder edges forming a flangeway, a spring-strip clampingly held in said flangeway and having a free end forming a reed and also adaptable as a rest base for the device, said port facilitating the passage of reed-actuated-sound therethrough and the removable engagement of a card therein.

2. In a toy noisemaker comprising a stamping of sheet metal having upper and lower arched portions, the combination of, means integral and cooperative with the stamping forming a combined port and a card-retainer-slot comprising a transverse upwardly directed slot having vertically spaced-apart edges which converge toward the respective ends thereof, the lower edge of said slot defining an upwardly directed gripping tongue adapted to engage a card inserted in said slot and laterally flex the same so as to frictionally bend it against the upper edge of the slot, the lower portion having bent-under edges forming a flangeway, a spring strip 10 clampingly held in said flangeway and having a free end forming a reed and also adaptable as a rest base for the device, said port facilitating the passage of reed-actuated-sound therethrough and the removable engagement of a card there- 15 in.
3. In a toy noisemaker comprising a stamping of sheet metal having upper and lower arched portions, the combination of, clip portions struck out of the upper portion and being bent in spaced pairs to standout and to form retaining means for a card and providing ports in the stamping, the lower portion having bentunder edges forming a flangeway, a spring-strip clampingly held in said flangeway and having a free end 20 forming a reed and also adaptable as a rest base for the device, said ports facilitating the passage of reed-actuated-sound therethrough when the free end is vibrated and the removable engagement of a card therein.
4. The device of claim 2 including means integral with the stamping for fastening the device to an article.
5. The device of claim 2 including means integral with the stamping for fastening the device to an article comprising a pin bent out of the upper end of the body portion.
6. In a toy noisemaker comprising a stamping of sheet metal having upper and lower arched portions, the combination of, means integral and cooperative with the stamping forming a combined port and a card-retainer-slot comprising a transverse upwardly directed slot having vertically spaced-apart edges which converge toward the respective ends thereof, the lower edge of 25 said slot defining an upwardly directed gripping tongue adapted to engage a card inserted in said slot and laterally flex the same so as to frictionally bend it against the upper edge of the slot, the lower portion having bentunder edges forming a socket having side and end grooves under said portion, a spring strip clampingly held in said socket grooves and having a free end and also a concaval convex indentation in its center portion forming a reed 30 and also adaptable as a rest base for the device, said upper and lower portions being angularly related with each other, said port facilitating the passage of reed-actuated-sound therethrough and the removable engagement of a card therein.
7. The device of claim 1 including means integral with the spring reed for fastening the device to an article comprising a pin bent out of the upper end of the reed and facilitating reed actuable tone change.
8. In a toy noisemaker comprising a stamping of sheet metal having upper and lower arched portions, the combination of, means integral and cooperative with the upper portion of the stamping forming a combined port and card-retainer-slot, the lower portion having 35 bentunder edges forming a socket having side and end grooves under said portion, a spring strip clampingly held in said socket grooves and having a free end and also a concaval convex indentation in its center portion forming a reed 40 and also adaptable as a rest base for the device, said upper and lower portions being angularly related with each other, said port facilitating the passage of reed-actuated-sound therethrough and the removable engagement of a card therein.
9. In a toy noisemaker comprising a stamping of sheet metal having upper and lower arched portions, the combination of, means integral and cooperative with the upper portion of the stamping forming a combined port and card-retainer-slot comprising a transverse upwardly directed slot having vertically spaced-apart edges which converge toward the respective ends thereof, the lower edge of 45 said slot defining an upwardly directed gripping tongue adapted to engage a card inserted in said slot and laterally flex the same so as to frictionally open it against the upper edge of the slot, the lower portion having bentunder edges forming a socket having side and end grooves under said portion, a spring strip clampingly held in said socket grooves and having a free end and also a concaval and convex indentation in its center portion forming a reed and also adaptable as a rest base for the device, said upper and lower portions being angularly related with each other, said port facilitating the passage of reed-actuated-sound therethrough and the removable engagement of a card therein.
10. The device of claim 1 in which the arched portions provide a sounding-board for the reed.
11. The device of claim 2 in which the arched portions provide a sounding-board for the vibratable reed.
12. The device of claim 9 in which the arched portions provide a sounding-board for the vibratable reed.

DAVID COHN.
